HANDBAG

Harry T. Silverman, Forest Hills, N. Y.

Application July 19, 1956, Serial No. 42,292

Term of patent 7 years

(Cl. D87—3)

FIG. 1.

FIG. 2.

FIG. 3.

FIG. 4.

FIG. 5.

FIG. 6.

Fig. 1 is a top plan view of a handbag showing my new design;

Fig. 2 is a bottom plan view thereof;

Fig. 3 is a front elevational view;

Fig. 4 is a rear elevational view;

Fig. 5 is an end view with the cover of the handbag in closed position; and

Fig. 6 is a view similar to Fig. 5 but showing the cover in the extreme open position.

I claim:

The ornamental design for a handbag, substantially as shown.
